D. FORSBERG.
NECKTIE HOLDER.
APPLICATION FILED SEPT. 12, 1917.

1,268,338.

Patented June 4, 1918.

UNITED STATES PATENT OFFICE.

DANIEL FORSBERG, OF BROOKLYN, NEW YORK.

NECKTIE-HOLDER.

1,268,338.

Specification of Letters Patent. Patented June 4, 1918.

Application filed September 12, 1917. Serial No. 190,914.

To all whom it may concern:

Be it known that I, DANIEL FORSBERG, a citizen of the United States, and resident of the borough of Brooklyn, in the county 5 of Kings, city and State of New York, have invented certain new and useful Improvements in Necktie-Holders, of which the following is a specification.

The object of this invention is to provide 10 a device of simple and efficient construction and operation upon and by means of which a necktie may be readily tied in semblance of an ordinary "four-in-hand" and securely held in that condition, and the device, together with the thus formed tie, may then 15 be detachably connected to the front collar button in proper relation to the collar of the wearer. Accordingly my invention comprises two hingedly connected members, 20 whereof one constitutes, in effect, a form upon which the necktie is appropriately tied and shaped in semblance of a "four-in-hand", and whereof the other, coöperating with the form member, constitutes a clamp 25 which is adapted to secure the tie in its tied condition and also to serve as a convenient means for attaching the device and its associated tie to the front collar button of the wearer, as will be hereinafter particularly described and claimed.

In the drawings—

Figure 1 is a front view of my improved necktie holder, showing in dot-and-dash lines the position of the necktie when it is 30 initially drawn between the two members of the holder.

Fig. 2 is a back view of the holder.

Fig. 3 is a longitudinal vertical section of the holder, indicating by dotted lines the 35 first step in the operation of forming a "four-in-hand" thereon.

Figs. 4 and 5 are front views illustrating succeeding steps in the operation of forming the tie on the device.

Fig. 6 is a front view of the completed tie as formed and secured on the device.

Fig. 7 is a rear view thereof.

Referring to the drawings, 1 and 2 designate the respective members of my improved necktie holder, said members being 50 pivotally connected similarly to the leaves of a hinge. The main or "form" member is of substantially triangular shape, its basal edge being preferably slightly concaved, as at 3, and having a pair of rearwardly-extending spaced and apertured lugs 4. The

other or "clamp" member of the device is of the general triangular form shown, its basal portion being provided with integral 60 teats or projections 5 which are rotatably seated in the apertures 6 of the lugs 4. The axis of the member 2 is spaced somewhat from the body of the member 1 and the basal portion of the member 2 is provided with an angularly disposed integral 65 lip 7, preferably toothed or serrated along its free edge, as shown, which lip, by proper movement of the clamp member, may be swung toward or from the back of the member 1 so as to clamp or release, as desired, the tie fabric interposed between the two members. The outer or tip portion of the member 2 is provided with an appropriate slot or opening 8 of sufficient width and form to receive the stem of a collar button; 70 thus providing a means for ready attachment of the device and its associated tie to the button.

To use the device above described the clamp member is first swung upward, as 75 illustrated in Figs. 1 to 4 inclusive. The tie is then folded and passed through the space between the two members so as to form the upstanding loop indicated by the dotted lines a in Fig. 3. This loop is then 80 swung down upon the front of the member 1, as indicated by the dotted lines a' in Fig. 3. The depending portion a^2 of the tie is then drawn to one side as indicated in Fig. 4; swung forwardly across the face of 85 the loop a' to produce the loop a^3 ; brought to the back of the member, and passed upwardly between the two members, as indicated in Fig. 5. The ends a^2 of the tie are then swung forwardly; passed down between the loops a' , a^3 of the tie, and drawn 90 tight, thus presenting the "four-in-hand" appearance illustrated in Fig. 6. Thereupon the member 2 is forcibly swung downward and the teeth of its clamping lip 7 are 95 thus caused to engage the tie material and bind it firmly and securely against the member 1, as indicated in Fig. 7. The device, with the tie properly formed and secured thereto as above described, is then slipped 100 under the front of the collar and the slotted lower portion of the clamp member is engaged with the collar button as above mentioned.

From the foregoing it will be seen that 110 my improved device consists of two parts only, which can be struck up from sheet

metal and readily hingedly connected, thus insuring economy of manufacture; and, further, that the device may be easily and quickly manipulated to perform efficiently the function of a "four-in-hand" tie-holder.

It is to be understood that I do not limit myself to the exact details of construction herein disclosed, as the same may be modified within the principle of my invention and the scope of the appended claim.

I claim—

A necktie holder of the character described, comprising a front member constituting a former for a four-in-hand tie and a rearward member coöperating with the front member to provide a clamp for the tie, said rearward member being spaced

from and hingedly connected to the front member so as to provide transversely of the holder, between the front member and the axial portion of the rearward member, a space through which the ends of the tie may be vertically drawn, said rearward member having adjacent to and movable with the hinge connection a clamping portion which by actuation of the rearward member on its axis may be swung across said space and into clamping or releasing relation with the front member, as desired, thereby clamping or releasing the interposed ends of the tie, said rearward member having also means for attachment to a collar button.

DANIEL FORSBERG.
